ALBERT E. EAGER, OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA.

APPARATUS FOR REAMING BUNG-HOLES OF BARRELS.

1,262,470.

Specification of Letters Patent.

Patented Apr. 9, 1918.

Application filed May 6, 1913. Serial No. 765,762.

To all whom it may concern:

Be it known that I, ALBERT E. EAGER, a citizen of the United States, residing at Philadelphia, in the county of Philadelphia and State of Pennsylvania, have invented 5 certain new and useful Improvements in Apparatus for Reaming Bung-Holes of Barrels, of which the following is a specification.

10 This invention relates more particularly to apparatus for reaming the bung holes of barrels after the preliminary boring, in order to enlarge and taper the opening for the reception of a suitable bung; but each 15 of the improvements composing the invention is intended to be secured for all the uses to which it can be applied with or without modification.

In reaming out a bung hole there is danger 20 that the cuttings consisting of fine shavings or particles of wood dust may enter the barrel; and, being difficult of removal, they are liable to remain (if they once get inside) and so to constitute a very objectionable litter and to contaminate the materials 25 which the barrel may eventually receive. In accordance with the present invention said shavings or fine particles are as formed removed by means of a current of air (produced by an exhaust) in a manner effectually to prevent entrance into the barrel.

The invention, which is particularly pointed out in the hereinafter written claims, will now be described in connection with the 35 accompanying drawings, it being premised that details are given by way of example and that additions, subtractions and other modifications can be made indefinitely so long as the substance of any one or more of said 40 claims is taken.

Figure 1 is an elevation partly in section, showing an apparatus embodying the invention in what is considered the best mode of carrying the principle of said apparatus into 45 effect;

Fig. 2 is an elevation of the reaming tool;

Fig. 3 is a vertical section through the reaming tool on line 2—2 of Fig. 5;

Fig. 4 is a section on the line 4—4 of 50 Fig. 3; and

Fig. 5 is an end view of the reaming tool. As illustrated in the drawings, the ream-

ing tool has a hollow conical body *a* tapering toward its lower end so as to fit with equal closeness the gradually enlarging hole 55 as it enters the same. On the exterior of the reamer body *a* is a series of spaced marks *b* (shown as circumferential grooves) which indicate to the operator the extent to which the tool has entered and consequently the size of the bung hole at any stage of the reaming operation.

The reamer body *a* has a slightly tapering interior space *c* open at top and bottom so as to form an air withdrawing passage. At 65 the lower end communication is established between this interior space and the exterior by the channel *d* in line with the tool axis. Lateral channels *e* also pass through the upper walls from without to the hollow interior. Other channels may well be placed at the lower end of the tool, as indicated in dotted lines at *d'*.

Throughout a portion of its length the wall of the reamer body *a* is provided in 75 its peripheral wall with a longitudinally disposed slot *f*; within which and projecting at its cutting edge beyond the reamer body is a longitudinally disposed knife *g*. The ends *g'* and *g''* of this knife are 80 clamped, one of them under the overhanging lip of a clip *h* secured by a screw *h'*, and the other under the lip of the wedge *i*; which is exteriorly threaded and held against the knife end *g''* by an interiorly threaded collar *j*. Thus the knife is held firmly in place and is yet easily loosened for adjustment or removal. The collar *j* is held from turning in use by a set-screw *j'*.

The upper end of the reamer body *a* is 90 exteriorly threaded to receive the collar *j* and also to enter the correspondingly threaded lower end of a tubular shaft *k*, which shaft is also laterally perforated at *k'* in order to form with the channels *e* through 95 ways for the passage of air to the interior of the reamer body at its upper portion above the knife. At *k''* are additional air inlets. Surface grooves *l* extending lengthwise of the reamer body *a* permit air to pass 100 into the interior of the barrel. The lower end of the reamer body *a* is squared at *a'* for the reception of a wrench.

The tubular shaft *k* is mounted to rotate

and also to slide freely in bearings m , m' and m'' of the bracket n . A drive shaft o driven by the drive pulley o' is likewise journalled in the bracket n and carries the 5 bevel gear p meshing with the bevel gear p' whose nave is connected by a spline and groove or other equivalent connection with the tubular shaft k so as to turn the latter while allowing it to slide freely through the 10 gear.

To the shaft k is rotatably secured a collar q ; and to this collar is attached the shift lever r provided with a counterweight r' and fulcrumed by means of the intermediate link 15 s to the bracket n , whereby the operator may lower and raise the shaft k and reaming tool to bring the latter into and out of working position.

The upper end of the shaft k rotates within 20 a tube t which rests at its lower end upon a plate u supported by the bracket n . The air tube t flares outwardly at its upper end in the form of a funnel, as at v ; where a number of peripheral openings v' are provided for the entrance of air from the outside.

With the large upper extremity of the funnel v is connected the lower end of the exhaust pipe w of much larger diameter than the air tube t , the tubular shaft k and the reaming tool; and at the upper extremity of the exhaust pipe w is arranged the exhaust fan x driven by the drive shaft y and the drive pulley z .

The operation is as follows: A barrel to be reamed having been positioned beneath the apparatus with its already bored (but unreamed or not sufficiently reamed) bung hole in line with the reaming tool, the operator, by means of the shift lever, lowers the 35 reaming tool into the bung hole, gradually entering the same until by means of the grooves b he perceives that the diameter is sufficiently large. As the rapidly rotating 40 tool enlarged the hole, air enters the tool both through the slot f and the bottom opening in end d (also through side channels d' , if used); and the fine shavings or particles of wood dust are caught by the air current 45 and are carried therewith into the tubular shaft k . Here they are caught by the additional air entering through the holes k' and k'' and are hurried into the funnel portion v ; whence, assisted by the air entering at v' , they are borne through the exhaust pipe w 50 and discharged through the exhaust fan x .

The number and size of the openings d , k' , k'' and v' and the diameter of the parts a , k , t , v and w are best so proportioned that 60 a steady and continuous draft is maintained at all points; so that the progress of the upwardly traveling particles of wood dust is uniform and there is no settling back or collecting in eddies or the like.

The apparatus will operate in a horizontal 65

or in an inclined position; but the vertical arrangement is considered most advantageous.

I claim as my invention or discovery:

1. A reaming tool which comprises first a 70 hollow body that is adapted to be held by one end and has both a longitudinally disposed slot through its peripheral wall and also an appropriately located air withdrawing passage, and second a longitudinally disposed 75 knife that is carried by said body and has its cutting edge opposite said slot beyond said body, the opening along said cutting edge being suitably proportioned relatively to said air withdrawing passage, and 80 the walls of the tool body being as a whole sufficiently close, for the withdrawal of the air from said tool body through said passage to induce an inflow of air which will convey all of said cuttings into and through 85 said tool body, so that a hole in a chamber wall, exemplified by the bung hole of a barrel, can be reamed by said tool without introducing reamer cuttings into said chamber to form an objectionable litter therein, 90 substantially as described.

2. A reaming tool which comprises first a hollow body that has a longitudinal slot through its peripheral wall, and second a longitudinally disposed knife that is carried 95 by said body and has its cutting edge opposite said slot beyond said body, in combination with means for holding said tool by one end and for rotating said tool, and also with air exhausting means which communicate with the hollow interior of said body for inducing air currents inward through said slot and for conveying away the cuttings made by said knife, substantially as described.

3. A reaming tool which comprises first a hollow body that is adapted to be held by one end, that has an air withdrawing passage at its holding end and an air inlet of smaller diameter at its opposite end and that 110 is further provided with a longitudinally disposed slot through the intermediate peripheral walls, and second a longitudinally disposed knife that is carried by said body and has its cutting edge opposite said slot 115 beyond said body, substantially as described.

4. A reaming tool which comprises first a hollow body that has an air withdrawing passage at one end, an air inlet of smaller diameter at its opposite end, and a longitudinally disposed slot through the intermediate peripheral wall, and second a longitudinally disposed knife that is carried by 120 said body and has its cutting edge opposite said slot beyond said body, in combination with means for holding said tool by its air withdrawing end and for rotating said tool, and also with air exhausting means which communicate with the hollow interior of 125 said body for inducing air currents inward 130

through said slot and said air inlet and for conveying away the cuttings made by said knife, substantially as described.

5. A reaming tool which comprises first a hollow body that is adapted to be held by one end, that has both a longitudinally disposed slot through its peripheral wall, and also an air withdrawing passage, and that, in addition to said slot and passage, has an air conveying channel for delivering air into the chamber into which the said body may be inserted, and second a longitudinally disposed knife that is carried by said body and has its cutting edge opposite said slot beyond said body, substantially as described.

6. A reaming tool which comprises first a hollow body that has a longitudinally disposed slot through its peripheral wall and is further provided with an air conveying channel for delivering air into the chamber into which the said body may be inserted, and second a longitudinally disposed knife that is carried by said body and has its cutting edge opposite said slot beyond said body, in combination with means for holding said tool by one end and for rotating said tool, and also with air exhausting means which communicate with the hollow exterior of said body for inducing air currents inward through said slot, and for conveying away the cuttings made by said knife, substantially as described.

7. A reaming tool which comprises first a hollow body that is provided with a longitudinally disposed slot through its peripheral wall, that has its hollow interior of tapering form, that is adapted to be held at the end which corresponds with the larger diameter of such taper, and that is provided at said holding end with an air withdrawing passage of correspondingly large diameter in continuation of said hollow interior and at its opposite end with an air inlet of a suitably smaller diameter to prevent the escape of cuttings through it against the inflowing air, and second a longitudinally disposed knife that is carried by said body and has its cutting edge opposite said slot beyond said body, substantially as described.

8. A reaming tool which comprises first a hollow body that is provided with a longitudinally disposed slot through its peripheral wall, that has its hollow interior of tapering form and that is provided with an air withdrawing passage of correspondingly large diameter in continuation of said hollow interior at the larger end of the taper and at its opposite end with an air inlet of a suitably smaller diameter to prevent the escape of cuttings through it against the inflowing air, and second a longitudinally disposed knife that is carried by said body and has its cutting edge opposite said slot beyond said body, in combination with means for holding said tool by the end

which corresponds with larger diameter of such taper, and also with air exhausting means which communicate through said passage with the hollow interior of said body for inducing air currents inward through said slot and for conveying away the cuttings made by said knife, substantially as described.

9. A reaming tool which comprises first a hollow body that has a longitudinally disposed slot through its peripheral wall, that is screw threaded at one end beyond said slot and that is provided at such end with a removable knife securing appliance in a portion of the screw threaded space, second a longitudinally disposed knife that is carried by said body, that fits at one end under said appliance and that has its cutting edge opposite said slot beyond said body, and third a collar that incloses said body and said knife securing appliances and occupies a part only of said screw threaded space, the screw threaded portion of said body thus extending beyond said collar and being applicable to the attachment of said tool to means for holding said tool by the end and for rotating said tool, substantially as described.

10. A reaming tool which comprises first a hollow body that has a longitudinally disposed slot through its peripheral wall, that is screw threaded at one end beyond said slot and that is provided at such end with a removable knife securing appliance in a portion of the screw threaded space, second a longitudinally disposed knife that is carried by said body, that fits at one end under said appliance and that has its cutting edge opposite said slot beyond said body, and third a collar that incloses said body and said knife securing appliances and occupies a part only of said screw threaded space, in combination with means for holding said tool by engagement with the projecting screw threaded portion of said body beyond said collar and for rotating said tool, substantially as described.

11. A hollow reaming tool having a longitudinally disposed slot through its peripheral wall and a longitudinally disposed knife whose cutting edge is opposite said slot, and a tubular shaft on one end of which said tool is mounted in such manner that the hollow interiors of said tool and shaft communicate with each other to form an air withdrawing passage, said tool and shaft being one of them at least provided with inlets for admission of air to its interior on the shaft side of the cutting portion of said tool, in combination with means for rotating said shaft and tool, and air exhausting means communicating with the interior of said shaft beyond said air inlets, substantially as described.

12. The combination with a hollow cut-

ting tool, and a tubular shaft on one end of which said tool is mounted in such manner that the hollow interiors of said tool and shaft communicate with each other to form 5 an air withdrawing passage, of a stationary conduit of larger diameter internally than said shaft, means for rotating said shaft and tool, and air exhausting means communicating with said stationary conduit, said 10 conduit being in communication with the interior of said shaft, and air inlets being provided near the place at which the air withdrawing passage through said tool, shaft and conduit is enlarged to the internal 15 diameter of said conduit, substantially as described.

13. A reaming tool which comprises, first, a hollow body of frusto conical form both 20 exteriorly and interiorly that is provided (a) with a longitudinally disposed slot through its peripheral wall, (b) with a passage through its larger end of correspondingly large diameter, (c) with a coupling 25 for attaching an air exhausting means to said passage, and (d) with a passage through the smaller end of said tool body of correspondingly small diameter, and, second, a longitudinally disposed knife 30 that is carried by said tool body and has its cutting edge opposite said slot beyond said tool body, the opening along said cutting edge and also the opening furnished by the smaller of said passages being suitably proportioned relatively to the larger of 35 said passages, and the walls of the tool body being as a whole sufficiently close, for the withdrawal of the air from said tool body through the larger of said passages to induce an inflow of air which will convey all of the 40 reamer cuttings into and through said tool body, substantially as described.

14. A reaming tool which comprises, first, a hollow body of frusto conical form both 45 exteriorly and interiorly that is provided (a) with a longitudinally disposed slot through its peripheral wall, (b) with a passage through its larger end of correspondingly large diameter, (c) with a coupling 50 for attaching an air exhausting means to said passage, and (d) with a passage through the smaller end of said tool body of correspondingly small diameter, and, second, a longitudinally disposed knife 55 that is carried by said tool body and has its cutting edge opposite said slot beyond said tool body, in combination with means for holding and rotating said tool, and also with means for exhausting the air from the interior of said tool body through the 60 passage at its larger end, the opening along said cutting edge and also the opening furnished by the smaller of said passages being suitably proportioned relatively to the 65 larger of said passages, and the walls of the tool body being as a whole sufficiently

close, for the withdrawal of the air from said tool body through the larger of said passages to induce an inflow of air which will convey all of the reamer cuttings into and through said tool body, substantially as 70 described.

15. A reaming tool which comprises, first, a hollow body of frusto conical form both exteriorly and interiorly that is provided 75 (a) with a longitudinally disposed slot through its peripheral wall, (b) with a passage through its larger end of correspondingly large diameter, (c) with a coupling for attaching an air exhausting means to said passage, and (d) with a passage 80 through the smaller end of said tool body of correspondingly small diameter and that is grooved exteriorly in a longitudinal direction, and, second, a longitudinally disposed knife that is carried by said tool 85 body and has its cutting edge opposite said slot beyond said tool body, the opening along said cutting edge and also the opening furnished by the smaller of said passages being suitably proportioned relatively to 90 the larger of said passages, and the walls of the tool body being as a whole sufficiently close, for the withdrawal of the air from said tool body through the larger of said 95 passages to induce an inflow of air which will convey all of the reamer cuttings into and through said tool body, substantially as described.

16. A reaming tool which comprises, first, a hollow body of frusto conical form both 100 exteriorly and interiorly that is provided (a) with a longitudinally disposed slot through its peripheral wall, (b) with a passage through its larger end of correspondingly large diameter, (c) with a coupling 105 for attaching an air exhausting means to said passage, and (d) with a passage through the smaller end of said tool body of correspondingly small diameter and that is grooved exteriorly in a longitudinal direction, and, second, a longitudinally disposed knife that is carried by said tool body and has its cutting edge opposite said slot beyond said tool body, in combination with 110 means for holding and rotating said tool, and also with means for exhausting the air from the interior of said tool body through the passage at its larger end, the opening along said cutting edge and also the opening furnished by the smaller of said 115 passages being suitably proportioned relatively to the larger of said passages, and the walls of the tool body being as a whole sufficiently close, for the withdrawal of the air from said tool body through the larger of said 120 passages to induce an inflow of air which will convey all of the reamer cuttings into and through said tool body, substantially as described.

17. A reaming tool which comprises, first, 130

a hollow body of frusto conical form both 5 interiorly and exteriorly that is provided (a) with a longitudinally disposed slot through its peripheral wall, (b) with openings in its peripheral wall at its larger end beyond the said slot, (c) with a passage through its larger end of correspondingly large diameter, (d) with a coupling for attaching an air exhausting means to said 10 passage, and (e) with a passage through the smaller end of said tool body of correspondingly small diameter, and, second, a longitudinally disposed knife that is carried by said tool body and has its cutting edge opposite 15 said slot beyond said tool body, the opening along said cutting edge and also the opening furnished by the smaller of said passages being suitably proportioned relatively to the larger of said passages, and the walls 20 of the tool body being as a whole sufficiently close, for the withdrawal of the air from said tool body through the larger of said passages to induce an inflow of air which will convey all of the reamer cuttings into 25 and through said tool body, substantially as described.

18. A reaming tool which comprises, first, a hollow body of frusto conical form both 30 interiorly and exteriorly that is provided (a) with a longitudinally disposed slot through its peripheral wall, (b) with openings in its peripheral wall at its larger end

beyond the said slot, (c) with a passage through its larger end of correspondingly large diameter, (d) with a coupling for attaching an air exhausting means to said passage, and (e) with a passage through the smaller end of said tool body of correspondingly small diameter, and, second, a longitudinally disposed knife that is carried by 35 said tool body and has its cutting edge opposite said slot beyond said tool body, in combination with means for holding and rotating said tool, and also with means for exhausting the air from the interior of said tool body through the passage at its larger end, the opening along said cutting edge and also the opening furnished by the smaller of said passages being suitably proportioned relatively to the larger of said 40 passages, and the walls of the tool body being as a whole sufficiently close, for the withdrawal of the air from said tool body through the larger of said passages to induce an inflow of air which will convey all 45 of the reamer cuttings into and through said tool body, substantially as described. 50

Copies of this patent may be obtained for five cents each, by addressing the "Commissioner of Patents,
Washington, D. C."

It is hereby certified that in Letters Patent No. 1,262,470, granted April 9, 1918, upon the application of Albert E. Eager, of Philadelphia, Pennsylvania, for an improvement in "Apparatus for Reaming Bung-Holes of Barrels," an error appears in the printed specification requiring correction as follows: Page 3, lines 28-29, claim 6, for the word "exterior" read *interior*; and that the said Letters Patent should be read with this correction therein that the same may conform to the record of the case in the Patent Office.

Signed and sealed this 14th day of May, A. D., 1918.

[SEAL.]

R. F. WHITEHEAD,

Acting Commissioner of Patents.
